UNITED STATES PATENT OFFICE.

HOWARD S. FOLKER, OF MILL VALLEY, CALIFORNIA, ASSIGNOR TO THE NATIONAL SAFETY APPLIANCE COMPANY, OF SAN FRANCISCO, CALIFORNIA, A CORPORATION OF CALIFORNIA.

MAGNETIC VALVE FOR RAILWAY-TRAIN CONTROLS.

Application filed February 7, 1923. Serial No. 617,552.

To all whom it may concern:

Be it known that I, HOWARD S. FOLKER, a citizen of the United States, and a resident of Mill Valley, county of Marin, State 5 of California, have invented certain new and useful Improvements in Magnetic Valves for Railway-Train Controls, of which the following is a specification.

This invention relates to improvements in 10 train control mechanism for use on railways and to that kind of mechanism in which there is provided magnetic means fixed on the roadbed co-operating with the magnetic means carried by the railway locomotive or other railway vehicle, by means of which when one magnet is in the field of the other a pneumatic train stop device is operated 15 to cause the application of the brakes, and also, if desired, to give an audible signal 20 to the engineer.

The above statement describes generally 25 that which is common between the present invention and the inventions disclosed in the patent granted to me on December 19, 1922 #1,439,081.

The invention hereinafter described and 30 claimed relates particularly, however, to an improved structure designated in the preceding paragraph as "magnetic means carried by the railway locomotive or other railway vehicle" and which in the above 35 specified patent I have chosen to call a "duplex control valve" which designation will be adhered to in this specification.

The principal object of the invention is 40 to provide a construction by means of which the magnetic circuit of each valve is completely isolated from the other and also from exterior magnetic circuits, this result being obtained by means of changes of construction of which the insulation introduced 45 at the central point of each inductor plane plays an important part. This construction in effect produces four inductor planes instead of two, as described in my prior patent above referred to.

Another object of the invention is to produce means for regulating the amount of magnetic flux through the armature so as to

adjust at will the holding power on the 50 armature in order to provide for the valve to open at varying pressures.

Other objects will appear from the subjoined specification and claims when read in connection with the accompanying drawings, in which:

Fig. 1 is a view partly broken away and in side elevation of a portion of a locomotive and also of a portion of a track and the control apparatus, showing the relative 60 positions of the apparatus carried by the locomotive and supported by the track.

Fig. 2 is a longitudinal section of the duplex magneto-control valve embodying my invention, showing also the conduits including the double heading release cock connecting the duplex magneto-control valve with the train stopping apparatus.

Fig. 3 is a section taken both on line 3—3 of Fig. 1 and line 3—3 of Fig. 2.

Fig. 4 is a plan view of the duplex magneto-control valve embodying my invention.

Fig. 5 is a view showing the magnetic circuit of the duplex control valve.

Fig. 6 is a perspective of the inductor 75 plane installation or assembly.

Fig. 7 is a fragmentary view in section showing the junction of the inductor plane laminations and the extension laminations.

Fig. 8 is a plan of an inductor plane lamination.

Fig. 9 is a plan of an extension lamination.

Fig. 10 is a plan of the inductor plane non-magnetic insertion strip.

Before referring particularly to the structure, it is deemed well to repeat that by means of the mechanism which will be hereinafter more particularly described, whatever magnetic circuits are now exterior to the circuits of the valve magnets do not affect the operation in the least and also the magnet controlling one valve does not affect the magnet controlling the other, as is the case with the structure of the duplex control valve described in my Patent #1,439,081 above referred to; this being due to the fact that in the former construction

- the two inductor planes served for both of the valves of the control valve unit, whereas in the present invention and improved construction each inductor plane is divided into
- 5 two substantially equal parts separated from each other by space and insulation thus affording in practice, the use of four inductor planes, two being utilized for the operation of one valve and two for the
- 10 operation of the other valve, although from the exterior of the structure it might appear upon casual inspection that each inductor plane extends unbroken throughout its entire length.
- 15 Referring briefly to Fig. 1, the locomotive apparatus consists of the subject-matter of the present invention, namely; magneto-duplex control valve unit C for receiving stop actuation from the track magnet unit T; 20 pneumatic stop valve S for causing application of the automatic brake, an application, Serial No. 617,553, for patent on which is executed and filed of even date herewith, the latter, that is the pneumatic stop valve S 25 with the valve R being for release and double heading.
- The track magnet T may be of any suitable design and construction; for instance, the track magnet disclosed in my prior
- 30 Patent No. 1,439,081 may be used, or else in place thereof the track magnet described and claimed in my co-pending application Serial No. 574,920 filed July 20, 1922, may be used.
- 35 For a complete understanding of the present invention it is only necessary to say that the track magnet unit T is properly encased, bolted on the track ties and centrally spaced between the rails with its top
- 40 level substantially at the upper surface of the rails and its sides substantially 13 inches from the gauge line of the rails; furthermore, it is so situated that there will be a clearance space of about five to six inches
- 45 between it and the inductor planes of the duplex control valve during the passage of a train.
- Normally the magnetic field of the track magnet is in place for automatic stop operation and it is diverted only for clear movements by energizing the electro-magnet control. As fully described in my patent and co-pending application above referred to, the deflection of the magnetic field results
- 50 through the energization of a neutralizing electro-coil control from a suitable signal battery controlled by a standard relay in the signal circuits. The installation of the electro-coil controls of the track magnet is
- 55 such that they will be energized on the approach of a train when the block ahead is clear or unoccupied, thus permitting the train to pass, but when the block ahead is occupied they will not be energized on the
- 60 approach of a train, thus permitting the

permanent track magnet to then act upon the train stopping mechanism which causes the automatic application of the brakes. This control is provided for either or both directions of traffic, but one magnet unit 70 being required for all controls.

While a suitable and efficient track magnet is of course necessary for operation of the complete installation of which the subject matter of the present invention forms a 75 part, it is believed that it is only necessary to say, in the interest of brevity, that either of the track magnets as described in my patent or application above referred to may be used.

Duplex control valve.

Coming now to a specific detailed description of the duplex control valve which is the particular subject matter of this invention, reference numerals are used to refer to the structural parts and reference letters are used to refer to the air chambers, pipes and conduits.

The duplex control valve consists of two 90 valves which are identical in construction, and in the interest of clearness it is only necessary at this point to describe but one, except where otherwise stated.

For each valve a pair of permanent magnets 20 hold an armature 13 and a connecting valve stem 12 against the main reservoir pressure in the chamber k. The pole pieces 23 are attached to the magnets 20 and to these are clamped pole piece plates 57 by 100 cap screws 58 and binder 48 and the screws 54. The extension laminations 28 are inter-assembled with inductor plane laminations 24 which latter extend in line with the longitudinal axis of the locomotive, so that they 105 pass over the track magnet unit at a clearance of five to six inches.

Attached to the valve 5 are pole piece dowels 17 which extend through the pole piece plates 57. The armature is held magnetically on the top of the dowels 17 and the valve stem 12 is fastened to the center of the armature 13 by means of a nut 11, and it extends downwardly through a guide bushing 8. A leather seat 22 with a small centrally located hole O is held against a seat in the valve by means of the bushing 9. The lower end of the valve stem 12 seats against the leather 22, thus sealing the opening O and preventing the escape of the main 110 reservoir air pressure in the chamber k to atmosphere so long as the armature 13 is held against the pole dowels 17 by means of the permanent magnets 20.

This structure as above described in general is ordinarily encased in a cast brass housing 2 and is suspended from a connection flange 29 to which it is bolted by suitable screwthreaded bolts and nuts 41 and 42. The flange 29 is suspended by rigid hangers 115 120 125 130

from the center sills of the locomotive tender, or in any other place convenience may make desirable.

As above stated, the duplex control valve 5 is installed to be carried in spaced relation above the tracks or running rails of the roadbed and extends in a line parallel to the rails.

The cast brass housing 2 is provided with four downwardly extending lugs through which pass the screwthreaded bolts 41 which secure the valve housing to the connection flange 29 from which it is suspended. On each side of the valve housing and integral with it, are four extending brackets, each of which is of the same construction and form and only one need therefore be described.

These brackets are provided with openings on the under side, in each of which are mounted extension laminations 28 of high permeability, such as transformer iron. These extension laminations have securing holes x and x' at each end. They are secured at the inner ends to the pole piece plates 57 by a suitable binder 48 and cap screw 58, and at the external or outer ends the laminations are interplaced between the inductor laminations 24, as illustrated in Fig. 6, and they are fastened by suitable screws 55 to the inductor plane casings, each of which is secured to the lower arms of the housing 2 by cap screws 31 and lock washers 32.

As above described, the structure of the two magneto-pneumatic valves 5 is the same, except for the fact that the duplex magnets 20 are arranged in pairs and one pair has a polarity opposite to that of the other pair.

The duplex magnets 20 are securely clamped to pole pieces 23 by magnet binders 21 and cap screws 14 which, as clearly shown in the drawings, pass through the magnet binder 21 which is recessed to fit the ends of the magnets and hold them in spaced relation to each other, all as clearly shown in Fig. 3.

The pole piece plates 57 are provided with holes through which cap screws 58 extend, and the housing is screwthreaded to receive the screwthreaded ends of the said screws 58, these screws being utilized to hold the extension laminations 28 to the binder 48 of the pole piece plates 57 securely in the housing 2.

The pole pieces 23 to which the magnets 20 are fastened, are secured to the pole piece plates 57 by means of the cap screws 54 which also hold a filler block 15 in position. Between the pole pieces 23 and pole piece plates 57 are placed adjusting shims 56 which are made of non-magnetic material, these adjusting shims being used to regulate the amount of magnetic flux through the armature 13.

The placing of the shims between the pole

pieces 23 and pole piece plates 57 introduce reluctance in the magnetic circuit—hence the more shims used the less flux through the armature 13, resulting in less holding power on the armature which will result in 70 causing the valve to open at lower pressures, also requiring less flux from the track magnet to neutralize the holding force on the armature 13.

All chambers and recesses of the interior 75 of the mechanism just described are concentric with the external surface of the valve stem. A valve stem guide bushing 8 fits snugly in the recess in the top of the valve fitting 5 and extending into the upper face 80 of the valve are two round cavities positioned diametrically opposite each other and into which cavities the pole piece dowels 17 are fitted. A small brass guide pin 30 is securely fastened in the center of one of each 85 pair of pole piece dowels and extends upwardly therefrom to serve as a guide to the armature 13, which armature seats or rests upon the top faces of the pole piece dowels 17. 90

The armature 13 is provided with a small hole through which the aforesaid brass pin 30 projects and is loosely fitted so that the armature may freely move in a vertical direction. This pin is also for the purpose of 95 preventing the armature from turning on the valve stem and away from the pole piece dowels 17. The valve stem 12 is preferably round in cross section and one end is screw-threaded and made smaller in diameter than 100 the other, the smaller end passing through a hole in the armature, the screwthreads thereon receiving and engaging with the valve stem nut 11 to hold the valve and armature structures together. 105

The armature 13 rests on the bottom of a cup-shaped element 10 which is first fitted over the small end of the valve stem 12, the wall 10' of the cup functioning to prevent any moisture that may pass by the stem 12 110 from flowing onto the armature 13. By means of the valve stem nut 11 the elements are secured together, yet the valve stem 12 is permitted to freely turn on the armature. 115

In assembling this structure the valve fitting 5 is inserted in the bottom of the housing 2 through the opening shown. The pole piece dowels pass through and snugly fit in holes in the under side of the magnet pole piece plates 57. The combined valve stem 120 12 with the attached armature 13 is entered into the valve fitting 5 and the armature is attracted and held fast on the top faces of the pole piece dowels 17 by the magnetic poles of the magnets 20. 125

The valve stem 12 extends down through the valve stem guide bushing 8 through the chamber L and the bottom end of the stem which forms the valve proper is flush with the top of the chamber L. The flexible 130

valve seat 22 preferably of leather, is securely clamped in the chamber *k* by a valve seat bushing 9, and in the center of the leather valve seat is a hole *O*, the area of which is less than the area of the face of the valve proper which, in this instance, is the lower end of the valve stem 12. The area of the valve exposed to air pressure is reduced, but the effective pressure on the end 10 of the stem is only slightly reduced due to the leather seat, because the leather is very flexible and depends upon the stem for support. The leather seat 22 being flexible, is forced by the air pressure against the end 15 of the valve stem 12, thus maintaining a tight seal therewith at all times when the valve is seated.

A cap 3 is constructed of cast brass and is secured to the under side of the duplex control valve by suitable bolts 54 and sealed by means of a gasket 40, and this cap is provided with air passages which will be hereinafter described.

Extending from the top face or flange 25 portions of the cap 3 and integral with it is a tubular or cylindrical element forming the chamber *i* which contains a strainer made up of the following parts: a bottom strainer 51, strainer shell 52 and a top strainer 50 within 30 which is placed curled hair 53. The strainer is fitted through the opening in the top of the cap, the opening being screw-threaded to receive the strainer nipple 4 which when screwed down tight in position with its 35 shoulder abutting against the top of the cap 3, forms an air tight closure. The strainer nipple 4 is fastened into the top of the cylindrical portion of the cap by suitable screwthreads and it has an air passage extending axially therethrough. The bottom 40 of the nipple 4 is provided with a strainer nipple tube 59 which passes down through the strainer tube 49. This structure is provided to carry all fluid pressure into the 45 chamber *i*, which chamber is for the purpose of collecting water and sediment. From the chamber *i* the fluid under pressure passes through the strainer 51, curled hair 53, strainer 50 and is led off through the 50 passages *j* which enter at the top of the strainer chamber to chamber *k* of each valve. The strainer nipple 4 extends up through an opening in the bottom of the valve housing 2, the top of the nipple being substantially 55 flush with the top of the valve housing cover 19.

In the bottom of the cap 3 is a screw-threaded opening to receive a plug 6. When the plug is screwed up tight into position 60 with its shoulder against the bottom of the cap 3, it forms the air tight chamber *i*. A hole is drilled partly through the plug 6 in the center thereof, extending into a hole 65 drilled radially through the shoulder of the plug, these holes being so situated as to

drain the dirt and water from the strainer when the plug 6 is unscrewed a few turns to expose the radial hole in its shoulder to the atmosphere.

The protecting casing 2 of the duplex 70 control valve is also provided with two rectangular channels into which filler blocks 15 are secured, which filler blocks are hollow and are packed with curled hair.

When the valve stem 12 is raised, air pressure is vented from chamber *k* into chamber *L*, through passages or ports *m*, through the curled hair packed in the filler blocks 15, thence to atmosphere through the ports *n*. The curled hair in the filler blocks 15 is provided to prevent roadway dust and dirt entering the valves through the exhaust ports or passages.

Protection to the train is provided in the event that the inductor planes in the duplex 85 control valve should be unduly bent or broken. The inductor plane casing 16 which contains the inductor plane laminations 24 is constructed with safety pipe nipples 25 and 90 27 running lengthwise thereof and secured thereto by screws 47 and 39. The pipes 25 and 27 are connected by means of breakable safety nipple couplings 45, which couplings are constructed of a brittle material which is made preferably from a Babbitt metal 95 consisting of lead and antimony. If the inductor planes are bent or broken the safety nipple couplings 45 will break and air pressure will be vented to the atmosphere, causing application of the brakes in exactly the 100 same way as if the valves 5 and 12 had been released by the armature in the regular way.

The structures by means of which the magnetic circuit of each valve is completely 105 isolated from the other and also from exterior magnetic circuits are clearly illustrated in Figs. 4 to 10, one of the magnetic circuits of the duplex control valve being illustrated in Fig. 5.

In Fig. 6 is illustrated the duplex control valve lamination assembly in which 24 indicates the inductor plane laminations in four groups, consisting preferably of seven each, and 28 the extension laminations in four 115 groups, preferably of six each, and 57 the pole piece plates with holes 58' for the reception of the bolts 58, and holes 54' for the reception of the cap screws or bolts 54. In the laminations are shown bolt holes 55' for the reception of the holding screws 55. The extension laminations 28 and the inductor plane laminations 24 are interlaid one within the other at *W*, as shown in Figs. 120 6 and 7.

Sheets or strips of non-magnetic material 46 fit inside of the inductor plane casings 16 on each side of the valve structure extending the entire length thereof and cover 130 the laminations on each side, the said sheets

- or strips being secured to the laminations and to the casings by means of screws 55 which secure the respective groups of laminations to the casings. Air insulating spaces 5 Z , Z' are thus provided between the adjacent ends of the groups of laminations, which spaces are bridged by the non-magnetic sheets or strips 46, the inductor plane laminations and the extension laminations 10 and the non-magnetic strips being each illustrated in Figs. 8 to 10.

The non-magnetic strip 46 forms the bottom of the casing 16 and its function is to hold the flexible steel laminations together 15 and to protect them. The non-magnetic strip is preferably of brass, though of course it could be made of fibre. When a brass strip is used the small air space at the edge of the casing is filled in with heavy paint.

20 By means of this construction four inductor planes are produced and this is a decided improvement over the two inductor planes of the devices of the prior art, for the reason that each pair of inductor planes 25 forms elements controlling a valve independent of the other. The magnet controlling one valve does not affect the magnet controlling the other valve inasmuch as there 30 is no magnetic circuit from the magnet of one valve to the armature of the other valve.

The magnets are so positioned that the duplex control valve will operate when the train is running in either direction, and furthermore, any adjustment to one valve does 35 not affect the other.

Double heading release cock and connections.

40 The double heading release cock R is a substantially rectangular bronze casting with two bosses, one at the top and one at the bottom of the main casting. The cock R is divided into two chambers between which is formed a slot to receive a lever handle 200. Tapered plug cocks 300 and 400 are entered through the bosses, the small ends of the plug cocks being flattened, both entering an opening in the lever handle 200 so that they may turn together when the 45 lever is operated.

Pressing against the larger ends of the 50 plug cocks 300 and 400 and encased in the bosses are springs 600 for the purpose of holding the plug cocks 300 and 400 normally into their seats. The bosses are 55 screwthreaded and fitting therein are two screw plugs 500 to hold the springs in place and cause them to exert pressure on the plugs 300 and 400.

60 The entrance ports to the chambers are suitably screwthreaded for connection by means of suitable pipes and fittings, the chamber in which the plug cock 300 operates being connected by pipe $d\ r$ leading to 65 the standard air brake double heading cock

A, and the chamber in which the cock 400 operates being connected by the pipe g to the train stop S.

In the plug cock 400 is a port so arranged that with the lever 200 in the double heading 70 release position and the air passage g' closed, any pressure building up in the air passage h' will, through leakage, vent to atmosphere through the port r' .

The double heading release cock R may 75 be so located on the engine that in order to gain access to it the engineer must dismount from his cab. This cock is also used to cut out the operation of the train stop mechanism when the air control is cut off from the 80 following engine or engines, when more than one engine is used on the train.

As will be clearly understood from the drawing the double heading release cock R has air passages, one of which is interposed 85 between the pipe g and the pipe h , the latter leading to the magneto-pneumatic duplex control valve C, and the other dr is connected by suitable pipes and vents to a special cock B which is attached to the engineer's brake valve A and exhausts to the 90 atmosphere.

The double heading release cock is so constructed that when in running position and the air passage h' which supplies the magneto-pneumatic valve C is open, the air passage dr is closed by means of the plug cock 300. Conversely, when the air passage h' is closed, the air passage dr is open and the double heading release cock is thus in double 95 heading and released position. The plug cocks 300 and 400 are attached to a common 100 lever handle 200 and operate simultaneously.

In order to permit restoration to normal 105 position of the duplex control valve units after exhausting to the air, the air passage h must be cut off, and this is done by turning the lever handle 200 to released position. When the control valve units have been 110 restored to normal position, the air supply 110 must be renewed, and this is also done by returning the lever handle 200 to running position. Failure to do so will leave the 115 brakes still unable to release, as the air is exhausting through the air passage dr and plug cock 300.

Operation.

The track is divided, as known, into a series of blocks insulated from each other 120 and a single permanent magnet unit is suitably installed within or at the entrance of each block in an insulated track section of one or more rail lengths.

The track magnet not shown in detail 125 preferably comprises a permanent magnet the magnetic field of which, when acting alone, is capable of controlling the operation of the train stopping means carried by the train every time a train passes over the mag- 130

net, since it has a polarity opposite to that of one of the valve magnets. The track magnets also comprise electro-coils associated with the permanent magnets and, when energized, capable of neutralizing or diverting the magnetic field of the permanent magnets. These electro-coils are energized whenever their circuit is closed by a train closing the track and line circuits of a system to provide clear signals, all as clearly described in the Patent No. 1,439,081 and application Serial No. 574,920 above referred to, and thus act to divert the free field of the track magnet, thereby preventing it from causing the train stop mechanism of the train to operate.

The installation of the electro-coils is such that the circuit of the coils will be closed and the coils will be energized on the approach of a train when the block ahead is clear and their circuit will not be closed by the approach of a train when the block ahead is occupied, thereby permitting the track magnet to act upon the train stopping mechanism. The reason the electro-magnet coils act upon the track magnet to divert its field is due to the fact that the former is stronger than the permanent track magnet and its polarity is opposite thereto.

The electro-coils may be operated in several ways: by the use of a relay, the circuit of which is controlled by the block ahead; or they may be operated by reason of the fact that they are in circuit with the rails of the block. In the latter instance, however, the battery would have to be very strong, and therefore to prevent excessive use of the battery they are preferably in circuit with a short track section of several rail lengths, and this circuit is closed upon the entrance of the first wheels therein, the wheels and axle acting as a switch in the circuit.

When a train passes over a track magnet its field acts upon the inductor planes of the duplex control valve F which causes a reversal of polarity in one of the armatures thereof, and thus permits the release of the armature from the poles installed as hereinabove described in the duplex control valve, thereby permitting the opening of the valve therein because of the air pressure normally exerted thereon, which action results in the application of the brakes and the stopping of the train.

Each magneto-pneumatic control valve comprises a permanent duplex horseshoe magnet with pole pieces extending upwardly and downwardly and terminating in broad flat pole pieces, and an armature normally attracted to the inner ends of the extended pole pieces. This armature has attached to it a brass stem which extends upwardly through guides, the lower end of this stem serving as a vent valve which, when the armature is attracted by the pole pieces of

the horseshoe magnets, closes the ports to atmosphere, and when the armature is released from the magnet control of the poles, the valve is opened by the air pressure which is constantly supplied thereto, thus allowing the main reservoir pressure, which is normally held in the chamber of the pneumatic valve, to be released to atmosphere.

Normally the magnet armature is attracted to the upper ends of the pole piece dowels and is held thereon by magnetic attraction which is stronger than the normal air pressure on the face of the valve. When the inductor planes of the duplex control valve magnet enter the free field of the track magnet, the polarity of the armature is reversed and the armature is repelled and the air pressure upon the lower face of the valve to which the valve armature is secured, causes the valve to open and thereby actuate the pneumatic valve, which results in the automatic application of the brakes.

Only one of the magneto-pneumatic control valves is operated at any one time, the magnets of the two halves, as hereinabove stated, being so arranged as to be of opposite polarity; that is, the south pole of one and the north pole of the other are in a line parallel to the center line of the track, and all the track magnets are installed in the same manner and the same polarity. One of the locomotive magnets, therefore, is always of a polarity opposite to that of the track magnet, regardless of the direction the locomotive is headed and also regardless of the position of the track magnet; thus the magnet of the locomotive duplex valve, which is of opposite polarity to the track magnet, is the one that is the operative locomotive magnet.

As the track magnet is of much greater magnetic strength than the locomotive magnet, the polarity of the armature of the operative control valve magnet is reversed, due to magnetic induction when the train enters the free field of the track magnet, and as long as it remains there, causes the armature to be released, thereby permitting the vent valve to open which results in the operation of the pneumatic valve.

The advantage of providing duplicate valve structures and duplicate magnetic structures, the latter of which it is to be noted are duplicates save as to their polarity, is to permit the operation of the train stop irrespective of the direction in which the train is going, and also irrespective of the position that the train magnet of a block may take when it is installed. Two valve units are provided to ensure that the polarity of at least one will always be opposite to that of the track magnet, regardless of the direction the locomotive is headed or running, and also opposite to the polarity of the track magnet regardless of its position

along the rails. The valve equipped with the magnets having an opposite polarity to that of the track magnet is the one that operates, and thus only one is operative at 5 any one time.

The construction, installation and operation of the magnetic elements of the entire system, both track and train, having been clearly described, reference will now be 10 made to the functioning of the air in the air ducts to produce the desired effects, which ducts are opened or closed by the operation of the magnets.

The main reservoir air flows from the 15 chamber in the train stop into the pipe *g*, through the release cock *R*, thence through the pipe *h*, strainer connection nipple *4*, connection nipple *59* of the control valve *C* into the chamber *i* which is provided to collect 20 water and sediment. From the chamber *i* the air then passes through the strainer *51*, the body of curled hair *53* and the strainer *50* into the passage *j*, thence to the lower end 25 of the valve stem *12* in the chamber *k*, which chamber is provided in the valve seat bushing *9*, pressure being built up in said chamber *k*.

Assuming that the duplex valve carried 30 on the locomotive is out of the free field of the track magnet, the armatures of the duplex control valve will be held down against the pole piece dowels by magnetic attraction. Due to the air pressure in the chamber *k* there will be an upward force 35 exerted on the end of the valve stem *12*, but the magnetic attraction on the armature is sufficiently strong to hold against this pressure.

In normal position the train pipe air pressure is built up in the ports, passages and 40 chambers provided therefor.

When the locomotive or railway vehicle carrying the duplex control valve passes over a permanent track magnet and the extending inductor planes of the duplex valve enter the free magnetic field of the track magnet, the polarity of the magnet of the operative valve in the duplex control valve is 45 reversed due to magnetic induction, the magnetism of the track magnet, as heretofore stated, being of much greater magnetic strength than that of the valve magnets. This condition remains just as long as the planes are in the free magnetic field of the track magnet, which is a sufficient interval to 50 apply the brakes and stop the train irrespective of the speed of the train. This reversal of polarity causes the armature in the duplex control valve to be released and repelled from the pole piece dowels, thereby 55 permitting the air pressure in the chamber *k* to force the valve stem *12* upwardly against the valve stem stop and to escape to atmosphere through the chamber *L* ports *m*, curled hair strainer *53* and vent ports *n*.

This operation in connection with the functioning of the train stop *S*, which is the subject matter of the application executed and filed simultaneously herewith, causes the brake pipe reduction necessary to apply 70 the brakes and the brake pipe exhaust to continue until the apparatus is restored to normal position.

After the device is operated and the operative field of the track magnet passed by 75 and the train brought to a stop, the double heading lever *200* of the double heading release cock *R* is manually moved to released position and the lever *200* being operated preferably from a position outside of the 80 cab, requiring the engineer to dismount therefrom. This operation of the lever *200* closes the lower plug cock, cutting off communication from the pipe *g* to the pipe *h*, and venting any remaining pressure in the 85 chamber *k* to the atmosphere through the port *r⁴* in the double heading cock, thus relieving the pressure on the end of the valve stem.

The weight of the movable valve stem 90 and nut causes the armature to drop by gravity into the operative field of the valve magnets and the armature is again attracted and restored to normal position and the 95 valve *5* is closed. The lever *200* of the double heading release cock is then returned to running position and the main reservoir pressure again builds up in the brake pipe.

While the lever *200* is in released position, 100 the upper plug cock *300* of the double heading release valve is open, allowing the brake pipe pressure to flow through the double heading cock, through the pipe *dr* and thence to atmosphere through the release valve *R*. The lever *200* must be returned to 105 running position for the purpose of closing the exhaust port to this cock, thereby ensuring that the lower cock will be open and in proper operative position. Failure to do so will leave the brake still unreleased 110 as air is exhausting through the pipe *dr* and plug cock *300*.

The returning of the lever *200* to running position allows the main reservoir pressure to build up again in the train stop *S*. 115

In double heading, in all engines following the first, the air conduit leading from the engineer's automatic control valve *A* is closed thus preventing the engineer from operating the train brakes. It is also necessary that the train stops on all following engines be made inoperative and the double release cock *R* provides this means. 120

When the handle *200* is placed in released or double heading position, the vent pipe 125 air from the stop to the control valves is cut off and the pipe leading from the engineer's control valve is closed first. Should the engineer fail to place the handle *200* in running position after double heading, the 130

brakes will be applied as soon as he turns the double heading cock to running position, because the brake pipe will be vented through the plug cock 300 of the double 5 heading release cock R.

Upon the automatic service application of the brakes the engineer can increase the rate of application, but he can only release 10 through the operation of the release cock that is under or in the locomotive cab.

As clearly set forth in the above description, air only controls the operation of the locomotive apparatus and no batteries or electric wires are used, which is a very great 15 desideratum in this art.

It has been found preferable to construct the valve parts of bronze.

Summary.

20 To sum up, the essentials of the operation are: The track magnet normally provides positive actuation of the automatic stop apparatus on the locomotive. The free magnetic field of the track magnet acts definitely on the particular control valve pole piece which has an opposite polarity to that of the respective poles of the track magnet when the train passes through its free magnetic field. This opposite polarity of 25 the control valve pole piece depends upon the direction in which the train is running, the magnets being so installed, as clearly described above, that when the train is running in one direction, one valve is operated, and 30 when the train is running in the other direction, the other valve is operated, each valve alone controlling the mechanism which causes application of the brakes. The magnet armature attached to the particular valve 35 to be operated is released and repelled, thus permitting air under pressure in the chamber h to exert itself on the under side of the valve rod 12 through the hole O in the diaphragm 22. The fluid under pressure then 40 carries with it the valve stem, thus opening the valve to cause the operation of the pneumatic stop valve S and consequent application 45 of the brakes.

As hereinabove described, the magnetic 50 circuit is clearly illustrated in Fig. 5, and Figs. 6 to 10 clearly illustrate the structure by means of which four inductor planes are provided (two pair), one pair governing the 55 operation of one of the valves, and the other pair governing the operation of the other valve of the duplex control valve.

As changes of construction could be made within the scope of my invention, it is intended that all matter contained in the above 60 description or shown in the accompanying drawing shall be interpreted as illustrative and not in a limiting sense.

Having now described my invention, what I claim as new and desire to secure by Letters Patent is:

1. A device of the type described which comprises a pair of vent valves, a pair of permanent magnets controlling said valves, a pair of inductor planes connected to the poles of one of said magnets, and a separate pair of inductor planes connected to the poles of the other of said magnets. 70

2. A device of the type described which comprises a pair of vent valves, a pair of permanent magnets controlling said valves, the polarity of one of said magnets being reversed to that of the other, a pair of aligned separate inductor planes, one connected to a pole of one of said magnets and the other connected to the adjacent pole of 75 the other magnet, and similar parallel aligned inductor planes similarly connected to the opposite poles of said magnets. 80

3. In a device of the type described, an inductor plane which comprises a casing 85 mounted in fixed position to move at a slight distance above a right of way, a number of horizontal laminations of magnetic material mounted in fixed position in said casing, and a cover of non-magnetic material for said 90 laminations.

4. An inductor plane which comprises a casing, a number of laminations of magnetic material in said casing, a cover of non-magnetic material for said laminations, extension laminations having their end portions interposed between the laminations in said casing and a cover of non-magnetic material for said laminations in said casing. 95

5. In a device of the type described, an inductor plane unit which comprises a casing mounted to be carried over and slightly spaced from a right of way, a pair of inductor planes mounted in fixed position in said casing, said inductor planes being formed of 100 horizontal laminations, laminated extensions extending sidewise from said planes, and a cover of non-magnetic material for said casing. 105

6. In a device of the type described, an inductor plane unit which comprises, a casing, a pair of independent inductor planes mounted in fixed position in said casing, and separate extensions extending sidewise from 110 the adjacent ends of said inductor planes. 115

7. A device of the type described which comprises a chamber, a pair of vent valves for said chamber, a pair of permanent magnets controlling said valves, the polarity of one of said magnets being the reverse of 120 that of the other magnet, a pair of independent inductor planes for each magnet, said planes being formed of laminations, and independent connecting laminations connected to the respective poles of said 125 magnets and having end portions interpositioned between the laminations of their respective inductor planes.

8. A device of the type described which comprises a permanent horseshoe magnet, 130

- 5 pole pieces for said magnet, pole piece plates for said pole pieces, shims between said plates and pole pieces, an armature spanning said plates, a vent valve controlled by said armature, and inductor planes connected to said pole piece plates.
- 10 9. A device of the type described which comprises a permanent horseshoe magnet, pole pieces for said magnet, pole piece plates for said pole pieces, shims between said plates and pole pieces, an armature spanning said plates, a vent valve controlled by said armature, laminated inductor planes for said magnets, and laminated conductor pieces attached to said pole piece plates and having their ends interplaced between the laminations of said inductor planes.
- 15 10. A device of the type described which comprises a permanent horseshoe magnet, pole pieces for said magnet, pole piece plates for said pole pieces, an armature spanning said plates, a vent valve controlled by said armature, laminated inductor planes for said magnets and extensions from said planes to the pole piece plates of the respective poles of said magnet.
- 20 11. A device of the type described which comprises a chamber, a valve for said chamber, a permanent horseshoe magnet, pole pieces for said magnet, pole piece plates for said pole pieces, an armature spanning said plates and controlling the position of said valve, a pair of inductor planes connected to said pole piece plates, a second valve for said chamber, a permanent magnet having a polarity reversed to that of the first magnet, and having similar pole pieces, plates and a separate pair of inductor planes.
- 25 12. In a device of the type described, a casing, a pair of aligned inductor planes in said casing having their adjacent ends slightly spaced, said inductor planes being formed of superposed laminations, a cover of non-magnetic material for said inductor planes, and a laminated extension for each
- 30 35 40 45 50 55 60 65 70 75 80 85 90 95 of said inductor planes having the laminations projecting between the laminations of its respective inductor plane.
13. A device of the type described which comprises a housing, a conduit in said housing, a strainer about said conduit, passages from said strainer, a pair of vent valves controlling the venting of said passages strainers between said vents and the atmosphere, a permanent magnet for each valve, the polarity of the magnet of one valve being reversed to that of the other, and a pair of independent inductor planes for each valve magnet.
14. A device of the type described which comprises a pressure fluid chamber, a vent orifice in said chamber, a valve stem member closing said orifice, a permanent magnet, pole piece plates for said magnet, non-magnetic shims between said pole piece plates and said magnet, and an armature spanning said pole piece plates and holding said valve stem.
15. A device of the type described which comprises a pressure fluid chamber, a vent orifice in said chamber, a valve stem member closing said orifice, a permanent magnet, an armature for said magnet and controlling said valve stem, and non-magnetic shims between said armature and said magnet.
16. A device of the type described which comprises a housing having passageways, a pair of vent valves for said passageways, magnetic control means for said valves, and a strainer between said valves and the atmosphere.
17. A device of the type described which comprises a chamber, an orifice in a wall of said chamber, a vent valve resting on and closing said orifice, magnetic means for holding said valve on said orifice, passages from said valve to the atmosphere, and a fibrous strainer in said passages.

HOWARD S. FOLKER.
